SPRING CONSTRUCTION FOR CHAIR SEATS OR THE LIKE

Filed July 23, 1929

UNITED STATES PATENT OFFICE

MAC LEVINE, OF MALDEN, MASSACHUSETTS, ASSIGNOR TO KAY MANUFACTURING CO.,
OF BROOKLYN, NEW YORK, A CORPORATION OF NEW YORK

SPRING CONSTRUCTION FOR CHAIR SEATS OR THE LIKE

Application filed July 23, 1929. Serial No. 380,338.

This invention relates to spring constructions such as are used for making chair or sofa seats, or the like, its object being to provide a unit which is durable, comfortable, and inexpensive. Spring constructions of various types have been used for this purpose, one type commonly used comprising rows of spiral springs, the lower ends of which are engaged by rigid bars, the ends of which bars may be fixed to the chair or sofa frame. Such bars, while serving to give a durable support for the springs, are nevertheless objectionable, in that they are unyielding and do not afford a seat of much comfort. It has been proposed to use resiliently flexible metal strips in place of bars, but as heretofore used, such supports have been liable to become permanently deformed when subjected to the stresses of use.

In accordance with the present invention, I provide a frame with which the resiliently flexible strips may be readily assembled, the assembled construction preferably being designed so that bending force may be transmitted from the strips to the frame, which may be made sufficiently rigid to withstand distortion. More particularly, the frame comprises spaced, parallel members, certain of which are suspended from arched members or trusses. These members serve as supports for the strips, which may be placed in spaced, parallel relation across the members, rows of spiral springs being mounted above the strips at the regions of contact of the strips with the members, with the lower end portions of the springs preferably serving to fix the strips to the frame, and the strips formed to act as seats for the lower ends of the springs.

With these and other features and objects in view, reference may be had to the embodiments of my invention described hereinafter in detail in conjunction with the accompanying drawing, wherein

Figures 1, 2 and 3 illustrate in perspective the frame alone, after its assembly with the strips, and the finished construction, respectively.

Figure 4 is a detail view showing the manner in which the strips are fixed to the frame.

Figure 5 is a side elevation of a modified form of construction.

The frame shown in Figure 1, which may be made of wire, comprises a one-piece structure 1 of generally rectangular form, the ends of which may be joined as by a ferrule 2. The structure 1 consists of a pair of opposite parallel members 3 for outer rows of springs, and a pair of opposite, upwardly arched members 4, from which latter, one or more members for one or more intermediate rows of springs may be suspended. As shown, a member 5 is arranged in parallel relation to and preferably midway of the members 4, its end portions 6 being bent upwardly and fixed to the members 4. In order to prevent the members 3 from being sprung apart by bending force transmitted through the member 5 to the arched members 4 and thence to the ends of the members 3, the ends of the members 3 are preferably tied together as by means of rods 7, thus forming trusses, from which the member 5 is suspended. A plurality of resiliently flexible metal strips 8, for instance three strips, as shown in Figure 2, may be placed across the parallel supporting members in spaced, parallel relation. The strips are preferably spaced apart at equal distances, so that the springs may be mounted at equal distances above the strips at the regions of contact of the strips and the frame. The strips are shown extending beyond the members 3, where they are bent upwardly at 9 and horizontally outwardly at their end portions 10, so that the construction may be suspended from a chair or sofa frame, the ends 10 being secured to the frame as by nails. As best shown in Figure 4, suitable upwardly bent portions 11 are preferably formed in the strips at their regions of contact with the frame, so that the lower end portion of a spiral spring 12 of the conventional compression type may be passed under the frame on one side 11a of each portion 11, thence over the strip, thence again under the frame on the other side 11b of the portion 11, and thence again over the strip. The lowermost convolution of the spring thus encompasses the portion 11 of the strip, and by its inherent resiliency remains fixed in this po-

sition while preventing longitudinal or lateral displacement of the strips, the portions 11 of the strips also serving as seats to fix the lower ends of the springs against displacement. After mounting the springs, a 5 suitable cushion support may be assembled on and fixed to the upper ends of the springs, that shown in Figure 3 comprising a rectangular frame 13 secured as by means of clips 14 to the uppermost convolutions of the outer springs. Supporting wires 14a may be strung across the upper ends of the springs and secured at their ends to the frame 13, the wires being provided with portions 15 projecting below the uppermost convolutions of the springs and engaged by links 16, which serve to keep the upper ends of the springs from lateral movement.

Should a plurality of parallel frame members for supporting a plurality of rows of springs be provided in place of the member 5 shown in Figures 1 and 2, between the frame members 3, the end portions 17 of these members may be bent angularly and brought together, as shown in Figure 5, and fixed at 25 the center of the arched members 4 as by a ferrule 18.

When weight is applied to the construction, the strips tend to flex at their central portions, but excessive bending is avoided, as excessive bending force is transmitted through members 5 to the arched members 4, which are able to resist it.

Certain embodiments of this invention having been disclosed, it should be evident to those skilled in the art that various changes and modifications might be made therein without departing from the spirit or scope of invention as set forth in the appended claims.

40 I claim:

1. The combination with a one-piece wire frame of generally rectangular form having opposite parallel members and opposite upwardly arched members, and a wire member suspended from said arched members and arranged between and parallel to said parallel members, of a plurality of resiliently flexible strips extending in spaced, parallel relation between said parallel members, and rows of spiral springs fixed above said strips at the regions of contact of said strips with said frame and serving to fix said strips to said frame.

53 2. The combination with a one-piece wire frame of generally rectangular form having opposite parallel members and opposite upwardly arched members, a wire member suspended from said arched members and arranged between and parallel to said first-mentioned members and wire members for tying together the ends of said first-mentioned parallel members, of a plurality of resiliently flexible strips extending in spaced, parallel relation between said parallel members, and 60 rows of spiral springs fixed above said strips

at the regions of contact of said strips with said frame and serving to fix said strips to said frame.

3. The combination with a one-piece wire frame of generally rectangular form having opposite parallel members and opposite upwardly arched members, a wire member suspended from said arched members and arranged between and parallel to said first-mentioned members, and wire members for tying together the ends of said first-mentioned parallel members, of a plurality of resiliently flexible strips extending in spaced, parallel relation across said parallel members, and rows of spiral springs fixed above said strips at the regions of contact of said strips with said frame and serving to fix said strips to said frame, the end portions of said strips extending beyond said parallel members and being formed for suspending the device from a chair frame or the like.

55 In testimony whereof I have affixed my signature.

MAC LEVINE.
